F. MURROW

Brush Handle.

No. 8,911.

Patented April 27, 1852.

8911

UNITED STATES PATENT OFFICE.

FREEMAN MURROW, OF WILLIAMSBURGH, NEW YORK.

BRUSH.

Specification of Letters Patent No. 8,911, dated April 72, 1852.

To all whom it may concern:

Be it known that I, FREEMAN MURROW, of Williamsburgh, Kings county, New York, have invented a new and useful Invention 5 in the Matter of Brushes for Whitewashing, Varnishing, Painting, &c.; and I do hereby declare that the following is a full, clear, and exact description thereof, reference being had to the accompanying drawing, and 10 letters marked thereon, forming a part of this specification.

Brushes constructed in the usual manner with fixed and immovable handles are inconvenient for many purposes for which 15 they are needed.

To remedy these defects, and to facilitate execution in the use of brushes, is the object of my invention; and it consists in so connecting the handle with the brush thereof 20 by means of a ball and socket and sliding joints, that the brush can be adjusted to any desired position and angle with its handle. The accompanying drawing represents perspective and sectional views of it as attached 25 to a flat brush, but it is also applicable to circular and other forms of brushes.

(a) is the frame of the brush in which the bristles are secured, which is beveled or wedge shaped on its sides.

30 (b b) are the braces or supports in which the socket for the ball (c) is formed. These where they connect with the frame (a) terminate in clasps (d, d) so as to embrace each side of, and slide on the frame (a). Said clamps are steadied and retained close 35 to the frame (a) by being provided with hooks or catches (represented in dotted lines) sliding in grooves in the way or guides (f f) secured to each side of the frame (a), only one of which is shown in the drawing.

(e) is a strap connecting the two braces (b b) together, giving them additional strength and forming a guard or shoulder 45 for the edge of the frame (a) to slide and rest against. Said braces where they connect with the handle terminate in the form of segments of hollow spheres or bowls (g, g) corresponding to the spherical form 50 of the ball (c). Firmly secured to one of

them is a guard (h) formed of a solid piece of metal, and encircling it and the two bowls is a belt (i) provided with a nut or head (j) on one end with a female screw cut in it, and in the other end of it is a hole, through 55 which the nut (j) is put when said belt is drawn close around the whole; and working in said nut (j) is a thumb screw (k) which when screwed in presses against the guard (h) causing said belt to draw said bowls 60 close around said ball, thus confining or fixing said ball in any desired position in its socket.

(l) is the ferrule for receiving the handle, which is firmly and strongly secured to the 65 ball by any suitable and well known means.

In one of the braces (b, b) is provided a hole and also a series of holes of corresponding size are bored in the edge of the frame (a) for the purpose of receiving a set pin 70 (m) and thus securing the braces at any desired position of adjustment with the frame.

Thus it will be seen that a brush constructed in the manner described can be adjusted to any position and angle with its 75 handle desired, and fixed there permanently by means of the thumb set screw (k) and the set pin (m), enabling the operator to point the brush in any direction from a right angle to the perpendicular, adapting it with 80 ease to the nature of the work to be performed.

Having thus fully described my invention for brushes, for whitewashing, varnishing, painting, washing painted cornice and walls, 85 etc., what I claim as my invention and desire to secure by Letters Patent, is—

The double adjustability of the brush by means of the combination of the ball and socket joint and the sliding joint, or their 90 equivalents, substantially as herein set forth.

In testimony whereof I, the said FREEMAN MURROW, have hereto subscribed my name in the presence of the witnesses whose names are hereto subscribed on this 22nd day of 95 November, A. D. 1851.

FREEMAN MURROW.

In the presence of—
C. M. BRIGGS,
JAMES WARNER.
